UNITED STATES PATENT OFFICE.

GEORGE E. CURTISS, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A CASE FOR VACUUM-BOTTLES.

49,139.

Specification for Design.

Patented June 6, 1916.

Application filed June 23, 1915. Serial No. 35,974. Term of patent 14 years.

To all whom it may concern:

Be it known that I, GEORGE E. CURTISS, a citizen of the United States, and a resident of New Britain, in the county of Hartford, State of Connecticut, have invented a new, original, and ornamental Design for a Case for a Vacuum-Bottle, of which the following is a specification, reference being had to the accompanying drawing, forming part hereof.

The figure is a side elevation of a case for a vacuum bottle illustrating my new design.

I claim:

The ornamental design for a case for a vacuum bottle, as shown.

GEORGE E. CURTISS.

Witnesses:

WILLIAM E. BAKER,
H. A. TRAVER.
